UNITED STATES PATENT OFFICE.

CARL E. BROWN, OF COLUMBUS, OHIO.

DESIGN FOR A HARP-BODY.

SPECIFICATION forming part of Design No. 32,652, dated May 15, 1900.

Application filed December 26, 1899. Serial No. 741,681. Term of patent 14 years.

To all whom it may concern:

Be it known that I, CARL E. BROWN, a citizen of the United States, residing at Columbus, in the county of Franklin and State of Ohio, have invented and produced a new and original Design for Harp-Bodies, of which the following is a specification, reference being had to the accompanying drawing, forming part thereof, and in which is illustrated in perspective my newly-designed harp-body.

As shown in the drawing, the leading or material feature of my design consists in the form or outline of the body when viewed from the front, one of the sides *a* of said outline rising vertically and at right angles from the horizontal bottom *b*, the opposite side line *c* inclining outward from said horizontal bottom, but of less height than the vertical side

line and the upper ends of these side lines being connected by a top *d*, which is in the form of a double or compound curve, as shown. The vertical side *a* is intersected in its upper portion by a transverse recess *e*.

Having described my invention, what I claim as new, and desire to secure by Letters Patent, is—

The design for a harp-body as herein shown and described.

In testimony whereof I have signed my name to this specification in the presence of two subscribing witnesses.

CARL E. BROWN.

Witnesses:

A. L. PHELPS,
W. S. MORROW.
